UNITED STATES PATENT OFFICE.

ISAAC W. LITCHFIELD, OF NEWTON, MASSACHUSETTS.

BATHING-CAP.

1,156,238.

Specification of Letters Patent.

Patented Oct. 12, 1915.

Application filed October 17, 1913. Serial No. 795,636.

To all whom it may concern:

Be it known that I, ISAAC W. LITCHFIELD, a citizen of the United States, residing at Newton, in the county of Middlesex and 5 State of Massachusetts, have invented an Improvement in Bathing-Caps, of which the following is a specification.

Bathing-caps, heretofore, have been provided with various means for tightening 10 their edge-portions about the head of the wearer to guard against leakage of water, but, so far as I am aware none have been successful in accomplishing this result, at least, to any great extent, and under all 15 conditions, unless tightened so tightly as to severely bind the head and cause discomfort to the wearer.

This invention has for its object to provide a bathing-cap with means at its edge- 20 portion which may be tightened about the head of the wearer and which will positively guard against leakage, and yet will not severely bind the head and cause discomfort to the wearer.

25 The invention comprehends the employment of a pneumatic engaging-portion at the edge of the cap, adapted to be inflated, and when inflated to positively yet yieldingly engage the head of the wearer and 30 conform to all irregularities thereof, and insure a water-tight joint or connection.

Figure 1 is a side elevation of a bathing-cap embodying this invention. Fig. 2 is a similar view with the inflating-means ar- 35 ranged for operation, a portion of the cap being broken away to illustrate the pneumatic edge-portion in section. Fig. 3 is a detail view illustrating a means for confining the tube which is employed to inflate the pneumatic edge-portion. Fig. 4 is an enlarged under side view of the cap and inflating-means. Fig. 5 is a sectional detail of the pneumatic edge-portion inflated, and, 40 Fig. 6 is a similar sectional detail of the 45 pneumatic edge-portion deflated.

The cap or hood 10, may be of any well-known or suitable construction. It has a pneumatic edge-portion adapted to tightly engage the head of the wearer, and, as here 50 shown, said edge-portion consists of a rubber tube 12, which is cemented or otherwise attached to the edge-portion of the cap, and which is longitudinally extensible and is adapted to be inflated to engage the head. 55 Said tube extends entirely around the edge-portion of the cap. A smaller tube 15 is

connected in any suitable manner, as for instance by a coupling, with the tube 12, and said tube 15 is made long enough to reach the mouth of the wearer when the 60 cap is placed on the head, as represented in Fig. 2, so that the wearer may, by blowing into the tube 15, inflate the tube 12 and cause it to engage the head as tightly as desired, and at least tight enough to produce 65 a water-tight joint or connection with the head. Although said tube 15 is quite short, unless it is detached, it is desirable to confine it when not in use, or hold it so that it will not be an annoyance to the wearer, 70 and, as here shown, the confining-means comprehends a short length of ribbon 20, attached at one end to the cap, its other end being free to be tied to another and similar short length of ribbon 21 to form a bow. 75 The ribbon 20 will be made wide enough to fold upon itself to confine the tube 15 when extended lengthwise thereof, as represented in Fig. 3, and being composed of rubber is flexible to conform to the bending of 80 the ribbon.

A closing-valve of any suitable construction will be provided by which to close the tube 15 by compressing it, thereby to hold the air in the inflated tube 12, and, as here 85 shown, a closing-valve of ordinary construction is represented comprising a base-plate 25 having ears 26 thereon to pivotally support a cam-lever 27, the cam 28 of which is designed to engage the tube 15 when said 90 tube is passed beneath it and above the base-plate. Said valve may be operated by moving the cam-lever on its pivot.

I claim:

1. As a new article of manufacture, a 95 bathing-cap having a longitudinally extensible pneumatic edge-portion adapted to be inflated for engaging the head of the wearer, substantially as described.

2. As a new article of manufacture, a 100 bathing-cap having an inflatable rubber tube attached to its edge-portion and extended entirely around it having means for inflating it for engaging the head of the wearer, substantially as described.

3. As a new article of manufacture, a 105 bathing-cap having a pneumatic edge-portion extended entirely around it and a flexible tube connected therewith with a closing- valve for inflating said pneumatic edge-portion for engaging the head of the wearer, substantially as described.

4. As a new article of manufacture, a valve for inflating said pneumatic edge-portion extended entirely around it and a flexible tube connected therewith with a closing-
5 valve for inflating said pneumatic edge-portion for engaging the head of the wearer, and means to confine said tube when not in use, substantially as described.

In testimony whereof, I have signed my name to this specification, in the presence of 10 two subscribing witnesses.

ISAAC W. LITCHFIELD.
